NONCLOGGING COAL CRUSHER

Frank E. Christopher and Harry Cappellanti,
Morgantown, W. Va.

Application August 2, 1946, Serial No. 688,063

6 Claims. (Cl. 241—111)

1

This invention relates to a non-clogging coal crusher which by its unique structure will prevent the crusher's rolls from being clogged should a harder substance than coal be deposited therein.

An object of this invention is to provide a coal crusher that will automatically operate to permit substance of foreign material to pass there through without clogging the crusher's rolls thereof.

Another object of the invention is to provide a coal crusher that is efficient in operation, durable in use and by its unique structure permits easy removal or repairs of the crusher rolls.

With the above and other objects in view the invention consists of the novel details of construction, arrangement and combination of parts more fully hereinafter described, claimed and illustrated in the accompanying drawings in which:

Figure 1 is a side elevation of an embodiment of the invention;

Figure 2 is a top plan view thereof;

Figure 3 is a rear view thereof;

Figure 4 is a sectional view on the line 4—4 of Figure 3;

Figure 5 is a sectional view on the line 5—5 of Figure 3;

Figure 6 is a sectional view on the line 6—6 of Figure 4;

Figure 7 is a detailed fragmentary view of the bearing slot for the power crusher;

Figure 8 is a front end view of the bearing for the power crusher;

Figure 9 is an interior side view thereof;

Figure 10 is a rear end view thereof;

Figure 11 is a sectional view on the line 11 of Figure 9;

Figure 12 is a perspective view of a rubber cushioning member.

Figure 13 is a modification of the invention and

Figure 14 is a sectional view on the line 14—14 of Figure 13.

Referring more in detail to the drawing the reference numeral 20 designates the frame or body of the coal crusher having the side walls 22, supporting legs 24 having flanged supporting feet 26 on the lower end thereof and the sides are joined by the fixed front end wall section 28 having the marginal flange 30 secured to the outer marginal side edge of the side walls 22 and rear end wall 32 having the depending portion 34 engaging the rear edges of the front legs 24 and the forwardly directed semi-circular projections 36 formed at the upper edge of the rear end wall and relatively spaced from each other for a purpose to be later described.

2

Secured to the wall 32 in vertical relation thereto and to the feet 26 at the lower end thereof are the outer upright guide members 38 which are provided at their upper ends with horizontal right angled outwardly extending flanges 39. Secured to the wall 32 intermediately of the members 38 are the inner guide members 40 which are relatively spaced from each other and the members 38 and bridged at their upper ends by 10 the cross member 42.

The sidewalls 22 are bridged at their upper ends by the transverse bar 44 and engaging this bar at its upper end and the wall section 28 at its lower end is the removable section 46 of the front end wall which is secured to the side walls 22 by fasteners 48. This wall is curved as shown to conform to the shape of the side walls 22.

Adjacent the upper end of the front legs 24 and the side walls 22 there are formed inclined 20 open ended slots 50 having a straight upper edge 52 curved bottom edge 54 and rounded bottom 56. These slots are formed to mount the transverse shaft 58 to which is secured the crusher roll 60 and it is to this shaft that power is applied from 25 a power source not shown.

The section 46 is provided so that this roll can be removed as desired for repair or the renewal thereof.

Removably mounted in the slots 50 are the 30 bearing members 62, having the bearing opening 64 for the shaft 58 and apertures 66 for receiving fasteners to secure the members to the side walls. The members 62 are inclined at their forward end at 68 and rounded at their rear end 35 at 70. The inwardly directed reduced portion 72 is received in the slots 50 and is chamfered at its rear to conform to the shaft 58. The portion 72 is provided with the substantial by triangular shaped depending projection 74 to close the slot 40 58 and the projection at its forward end is bevelled at 76 and it will be seen that when the members 62 are in position and secured by fasteners 78 the projection 74 engages curved bottom edge 54 of the slot 50 and the forward edge 68 conforms to the forward edge of the sidewalls and the members 62 is provided with an offset 80.

The upper edge and downwardly curved rear edge and lower straight edge of the side walls are provided with conforming flanges 82 and bearing flanges 84 in which are journaled the transverse shaft 86 of the roller adjuster frame 88 and removable upper bearing plates 90 secured to the side walls by fasteners 92 conform to the shape of the side walls and the flanges thereon.

55 The roller adjusting frame 88 is loosely mounted on the shaft 86 and comprises arcuate side members 94 having cutouts 95 in the convex inner

edge thereof which are bridged at their upper end by the substantially curved cross member 96 and at their bottom by the substantially curved cross member 98 and on the concave side of the members 94 are provided removable bearing plates 100 which are secured to the members 94 by fasteners 102 and serve to journal the relatively spaced axles 104 of the crusher rolls 106, which are in parallel relation to each other and confront the crushing roll 60 and also permits removal of the rolls as desired. The member 98 is provided with spaced recesses 108 to receive the apertured tongues 110 of the arcuate shaped arms 112 and thus the arms are connected to the shaft 86.

The arms are slotted at their lower ends at 114 to receive the tension rods 116 which are connected at their opposite apertured ends to the lower ends of the members 94 by pivot bolts 118 and a spring 120 on the rods 116 engaging a shoulder 122 thereof, at one end and the arms at the other ends tension the arms 112 by means of manipulation of the nuts 124 on the forward threaded end of the rods 116.

The arms 112 are joined by the curved partition 126 and have forwardly extending projections 128 formed thereon which extend forwardly of the arms to be received between the outer and inner guide members 38 and 40 respectively.

Secured to flanges 39 of the members 38 and the cross members 42 by fasteners 130 is the transverse member 132 having blocks 134 on the undersurface thereof to be seated between the members 38 and 40 and semicircular forwardly extending apertured projections 136 which are 35 in alignment with the projections 36.

Positioned intermediate the members 38 and

crushing of the coal between this roll and the crushing rolls 106. Manipulation of the members 138 or the screws 150 determine the size of the coal as it passes through the crusher to be discharged at the bottom thereof.

Thus a crusher has been provided that due to its unique structure will not clog and will crush coal into various sizes.

It is believed that the operation and construction of the crusher will be apparent to those skilled in the art and it is to be understood that changes in the details of construction, arrangement and combination of parts may be resorted to provided they fall within the spirit of the invention and the scope of the appended claims.

Having thus described the invention what is claimed as new and desired to be secured by Letters Patent is:

1. In a coal crusher having a frame having side walls and supporting feet therefor the improvement comprising a crusher roll mounted in said frame transversely thereof, a crusher roller adjusting frame mounted in said first frame, a plurality of crusher rolls positioned in said crusher roller adjusting frame and transversely thereof and confronting said first crusher roll, means for tensioning said crusher roller adjusting frame connected to the lower ends thereof, a shaft supported by said side walls for pivotally mounting the upper end of said crusher roller adjusting frame thereon, arcuate shaped arms receivable at their upper end on said shaft and extending from said shaft outwardly of the crusher rolls in said crusher roller adjusting frame, a projection on said arms at right angles thereto and outwardly thereof, cushioning means for said arms engaging said projection and sides and means

6. The invention as in claim 2 wherein the operating means engaging said projection comprises a plurality of cushioning means positioned on opposite sides of said projection and means passing through said projections and said cushioning means for retaining the same in position.

FRANK E. CHRISTOPHER.
HARRY CAPPELLANTI.
